AGITATOR FOR A WASHING MACHINE

Thomas R. Smith and Charles W. Burkland, Newton, Iowa, assignors to The Maytag Company, Newton, Iowa, a corporation of Delaware

Application February 4, 1957, Serial No. 44,749

Term of patent 14 years

(Cl. D49—1)

Figure 1 is a side elevational view of a washing machine agitator showing our new design; and,

Figure 2 is a top plan view of the agitator shown in Figure 1.

We claim:

The ornamental design for an agitator for a washing machine, as shown.
